UNITED STATES PATENT OFFICE.

WILLIAM W. DEAN, OF NORTH RIDGEVILLE, OHIO, ASSIGNOR TO THE DEAN ELECTRIC COMPANY, OF ELYRIA, OHIO, A CORPORATION OF OHIO.

GOVERNING DEVICE.

1,039,107.

Specification of Letters Patent. Patented Sept. 24, 1912.

Application filed August 16, 1911. Serial No. 644,447.

To all whom it may concern:

Be it known that I, WILLIAM W. DEAN, a citizen of the United States, residing at North Ridgeville, in the county of Lorain 5 and State of Ohio, have invented certain new and useful Improvements in Governing Devices; and I do hereby declare the following to be a full, clear, and exact description of the invention, such as will enable those 10 skilled in the art to which it appertains to make and use the same.

My invention relates to governing devices and more particularly to circuit controlling devices, though I may, of course, 15 employ my device wherever a device of this character finds a use. When used as a circuit controller, the device may be associated with the armature shaft of a current generator and may control a circuit associated 20 therewith. When associated with a rotary member of this character, I mount the flexible member upon the rotatable member in such a way that a part of such flexible member may move in the direction substantially 25 parallel to the shaft and control the circuit or other means governed by the device.

The object of my invention and the invention itself will be best understood by reference to the particular embodiment illustrated in the accompanying drawings, while the scope of the invention will be better understood from the appended claims.

Figure 1 is an elevation of the device. Fig. 2 is an end elevation. Fig. 3 is a 35 section.

While I have shown my invention employed with an electric generator and as controlling an electric circuit, it will be understood that I may employ it with any 40 suitable form of mechanism and impose upon it any duty which it is capable of performing without departing from the spirit of the invention, unless otherwise indicated by the claims.

45 In the form shown, I illustrate at 1 a dynamo; 2 is the armature shaft, which would here be a rotating or rotary member, though this might as well be a portion of an engine, or some other mechanism. A movable member 3, which may be flexible, and is 50 preferably as shown in the drawing, a flexible spring, is carried by the rotary member 2. This member may be mounted upon the rotary member by means of a supporting member 4, which is here shown as disk

shape, and which bears a hollow circular boss 5 at the center, into which the end of the shaft 2 fits and to which the member 4 may be fastened by set screw 6. The part 4 is perforated at 7, preferably diametrically opposite the point at which the member 3 is attached to the support. The member 3 is attached preferably at one end by a suitable means such as screws 8. A part of the member 3, preferably the end 9 which is opposite the fastened end, is free to move in a direction substantially parallel to the axis of rotation of the shaft 2. A weight 10 may be mounted upon the free end 9 of the flexible member, extending through the opening 7 with its center mass outside of the vertical plane in which the flexible member is attached to the support. The support is cut away, as shown at 11 for a purpose to be described. The parts are so 60 adjusted that when the armature shaft reaches a certain rate of rotation, the centrifugal force will tend to throw the weight 10 outward, being restrained in that direction, it will move in a direction substantially parallel to the axis of rotation of the shaft, moving the free end of the member 3 with it and performing the duty which has been imposed upon the parts. In the form shown, its duty consists 65 of closing an electric switch "S". This switch is formed by a contact 12 connected to the frame 13 by a contact support 14 and a contact 15, which in the form shown is carried upon a second flexible member 16. 70 This flexible member consists of a spring mounted upon the frame 13. The two flexible members are connected together by a stud 17, which, in the form shown, is applied to the member 3, substantially in the 75 axis of rotation of the rotary member 2, so that the support may be rotated without carrying the fastening means 17 along with it. A bearing 18 is mounted upon the member 3 in the recess 11 in the support 4, into 80 which one end of the fastening means 17 is journaled. I prefer to stiffen the ends of the two flexible springs and best attain this object by turning up the edges of these 85 members, as shown at 30. The flexible member 16 is stiffened by a plate 31 fastened to the under side thereof by rivets 32, though, of course, these stiffening means are not essential. Thus, in the form shown, when 90 the rotary member rotates at a pre-deter- 95 100 105 110

mined speed, the member 3 will be carried outward, closing the switch "S".

It will be obvious to those skilled in the art that numerous and extensive departures 5 from the form and details of the embodiment of the invention here shown, may be made without departing from the spirit of the invention, the same being herein shown solely for the purpose of clearly illustrating one specific embodiment of the invention.

Having thus illustrated and described one particular embodiment of my invention, what I wish to claim is:

- 15 1. In a circuit controller, the combination with a rotating member of a supporting member carried thereby, a flexible member carried by said supporting member and attached thereto, one end of said flexible member being free, a weight carried by the free end of said flexible member, a frame, a flexible contact carrying member mounted in said frame, a contact carried thereby, means to connect said flexible member with 20 said flexible contact carrying member, said means being in the axis of rotation of the rotating member and a stationary contact adapted to coöperate with said first named contact to form an electric switch, said 25 weight being moved by centrifugal force to close said contacts when the rotating member reaches a predetermined speed.

2. In a circuit controller, the combination with a rotating member, a supporting member, a flexible member mounted on said supporting member, perpendicular to said rotating member, a part of said flexible member being free to move parallel to the long axis of said rotating member, a frame, a 30 second flexible member mounted at one end on said frame and connected to said first named flexible member, a contact carried by said second named flexible member, a second contact on said frame coöperating with said 35 first contact, said contacts constituting an electric switch controlled by said first named flexible member, said movable part of said flexible member being moved when the rotating member reaches a predetermined 40 speed to operate said switch.

3. In a circuit controller, the combination with a rotating member, a flexible member carried by said rotating member, one end of said member being free to move substantially parallel to the long axis of said rotating member, a weight carried by the free end of said flexible member, a frame, a contact carrying member mounted in said frame, a contact carried thereby, means to

connect said flexible member with said contact carrying member, said means being in the axis of rotation of the rotating member and a stationary contact adapted to coöperate with said first named contact, said weight being moved by centrifugal force to operate 60 said switch when the rotating member reaches a predetermined speed.

4. In a device of the class described, the combination of a rotating member, a movable member connected to said rotating member on one side thereof, a weight on said movable member on the other side of said rotating member, said weight being moved in a direction substantially parallel to the axis of rotation of said rotating member, when the rate of rotation of said member reaches a predetermined amount, and a circuit controller governed by said movable member.

5. In a device of the class described, the combination of a rotating member, a disk shaped support carried upon one end thereof, a flexible member attached at one end near the edge of said support and free to move at the other end, a weight mounted on the free end and adapted to move through an opening in the support when the centrifugal force has reached a predetermined value, and a switch controlled by said flexible member.

6. In a device of the class described, the combination of a rotary member, a disk shaped supporting member mounted on one end of said rotary member, said supporting member having an opening therein near the periphery thereof, a flexible spring attached at one end, near the periphery of the supporting member and extending substantially diametrically across the disk and being free at the other ends, a weight mounted on the free end and extending through the opening in the disk, the major part of the weight being on the side of the support opposite the side upon which the spring is mounted, a frame, a second flexible spring mounted on said frame, means to connect said flexible springs together, said means being applied in the axis of rotation of said rotary member, a contact carried by said second flexible member, a second contact carried by said frame, said contacts constituting an electric switch controlled by said rotary member.

In testimony whereof, I affix my signature, in the presence of two witnesses.

WILLIAM W. DEAN.
